United States Patent Office

Des. 233,879
Patented Dec. 10, 1974

233,879

HANDLE FOR AN APPLICATOR

John R. Howard, West Chicago, Ill., assignor to Turtle Wax, Inc., Chicago, Ill.

Filed June 15, 1973, Ser. No. 370,338

Term of patent 14 years

Int. Cl. D7—05

U.S. Cl. D7—178

FIG. 1

FIG. 2

FIG. 3

FIG. 1 is a top plan view of handle for an applicator incorporating my new design;

FIG. 2 is a front elevational view thereof, the rear being identical thereto;

FIG. 3 is a side elevational view, the opposite side being identical thereto.

The broken lines in FIGS. 2 and 3 are for illustrative purposes only and form no part of the claimed design.

I claim:

The ornamental design for a handle for an applicator, as shown and described.
